RETRIEVABLE BRIDGING PLUG FOR SEALING A WELL CASING BORE

McHenry Davis, San Marcos, Tex., assignor of one-half
to Ollie P. Davis and Tommy G. Davis, jointly, both
of Houston, Tex.

Filed Jan. 5, 1965, Ser. No. 423,504
5 Claims. (Cl. 166—63)

ABSTRACT OF THE DISCLOSURE

An expandable bridging plug which is releasably latched to a lowering unit for lowering into a well casing. Detonation of an explosive charge contained in the lowering unit causes release of a compressed gas contained in the plug for expanding and sealing the plug in the well casing and for unlatching the lowering unit from the plug, so that said lowering unit can be recovered. A retrieving unit which is subsequently lowered into the plug releases the compressed gas to unseal the plug from the well casing and latches itself to the plug so that the plug is retrieved with the retrieving unit.

This invention relates to a bridging plug capable of being lowered to a desired position in the bore of a well casing, and to be expanded while so located for clamping the plug to the casing wall for sealing the bore of the casing.

Another object of the invention is to provide a retrievable plug including a lowering unit by which the plug is supported while being lowered to a desired location in the casing bore and which includes means to effect expansion of the plug after it has been lowered to a desired depth for sealing the casing bore, and for unlatching the lowering unit from the plug so that said unit can be retrieved from the plug while the plug remains clamped to the well casing.

A further object of the invention is to provide a retrieving unit which may be subsequently lowered into the well casing and into engagement with the bridging plug for releasing the plug for clamping engagement with the well casing and for latching the plug to said retrieving unit whereby the plug can be recovered from the well casing with the retrieving unit.

Still a further object of the invention is to provide valve means forming a part of the retrievable plug to release the pressure of hydrostatic well fluids and circulating fluids from a part of the plug to facilitate entrance of the retrieving unit into said part.

Various other objects and advantages of the invention will hereinafter become more fully apparent from the following description of the drawings, illustrating a presently preferred embodiment thereof, and wherein:

FIGURE 1 is a fragmentary view primarily in side elevation and partially in longitudinal section showing the bridging plug in an applied position in a well casing;

FIGURE 2A is an enlarged fragmentary longitudinal sectional view, partly in elevation, of an upper part of the retrieving unit;

FIGURE 2B is an enlarged longitudinal, substantially central vertical section view of the lower portion of the lowering unit and the upper portion of the retrievable bridging plug;

FIGURE 2C is a fragmentary longitudinal substantially central vertical sectional view of the remaining, lower portion of the plug;

FIGURE 3 is an enlarged longitudinal substantially central vertical sectional view, partly in elevation, showing a part of the structure as seen in FIGURE 2B and a part of the structure as seen in FIGURE 2C, with cer-

2

tain of the illustrated parts in different positions from the positions of said parts in FIGURES 2B and 2C;

FIGURE 4 is an enlarged detail sectional view of a part of the structure as seen in FIGURE 2B;

FIGURE 5 is an enlarged cross sectional view of the retrievable plug taken substantially along a plane as indicated by the line 5—5 of FIGURE 2C;

FIGURE 6 is a fragmentary longitudinal sectional view of a part of the retrievable plug taken substantially along the line 6—6 of FIGURE 5;

FIGURE 7 is a cross sectional view of a part of the plug taken substantially along a plane as indicated by the line 7—7 of FIGURE 4 and on a greatly enlarged scale;

FIGURE 8 is an enlarged cross sectional view through a part of the plug, taken substantially along a plane as indicated by line 8—8 of FIGURE 2C;

FIGURE 9 is an enlarged bottom plan view of certain of the parts of the plug, shown detached therefrom;

FIGURE 10 is an enlarged cross sectional view illustrating in detail certain of the parts as seen in FIGURE 2C;

FIGURE 11 is a view similar to a portion of FIGURE 3, on a slightly enlarged scale relative thereto, and showing a part of the lowering unit replaced by parts to form the retrieving unit;

FIGURE 12 is an enlarged front elevational view, partly in section, of a double check valve constituting a part of the retrievable plug;

FIGURE 13 is a longitudinal, substantially central sectional view thereof, taken substantially along the line 13—13 of FIGURE 12;

FIG. 14 is a top plan view of the check valve on a reduced scale;

FIGURE 15 is a cross sectional view of the check valve, taken substantially along a plane as indicated by the line 15—15 of FIGURE 13, and on a reduced scale;

FIGURE 16 is a similar view taken substantially along a plane as indicated by the line 16—16 of FIGURE 13; and

FIGURE 17 is a similar view taken substantially along a plane as indicated by the line 17—17 of FIGURE 13.

Referring more specifically to the drawings, the retrievable plug in its entirety and comprising the invention is designated generally 20 and includes a bridging plug 21 and a lowering and anchoring unit 22.

The bridging plug 21 includes a sleeve 23 constituting the lower end thereof, as best seen in FIGURES 1 and 2C, and which includes a top portion 24 and a bottom portion 25. An intermediate portion 26 extends between the end portions 24 and 25 and is provided with circumferentially spaced slots 27 which extend from end to end thereof. A clamping bar 28 is mounted in each slot 27. Each bar 28 has a set of teeth 29 disposed crosswise of one end thereof and which face toward the other end of said bar. The clamping bars 28 are arranged so that the teeth 29 of adjacent bars are disposed at the opposite ends of the intermediate portion 26 and face in opposite directions. An elastic tube 30, formed preferably of plastic or rubber, lines the interior of the intermediate portion 26 and is bonded thereto and to the inner surfaces of the clamping bars 28.

The bridging plug 21 includes a collar 31 which is disposed above and spaced from the sleeve 23. An elastic tube 32 has a lower portion extending through the sleeve 23 internally of the tube 30, and an upper end which is disposed in the collar 31. The bottom sleeve portion 25 defines a downwardly opening cup in which a plug 33 is threadedly mounted, as seen at 34. The lower end of the tube 32 is clamped, as seen at 35 in FIGURE 2C, between parts of the bottom sleeve portion 25 and the plug 33. A plug 36 is threaded downwardly, as seen

at 37, into the upper portion of the collar 31, and the upper end of the tube 32 is clamped, as seen at 38, between opposed portions of the collar 31 and plug 36. A plurality of sealing rings 39 are mounted on the tube 32 between the top sleeve portion 34 and the collar 31. The sealing rings 39 are formed of plastic or rubber of substantial hardness but are capable of being stretched. The upper portion of the top part 24 of the sleteve is internally recessed, as seen at 40, to receive a hard rubber or plastic abutment ring 41 and the lower end of the collar 31 is internally recessed, as seen at 42, to accommodate a similar abutment ring 43. Sealing rings 39 are retained in spaced apart relation to one another and to the abutment rings 41 and 43 by resilient spacing rings 44, each of which preferably comprises an annular coil spring 45 encased in a rubber tube 46, as best seen in FIGURE 10.

The plug 30 has a depending externally threaded boss 47 and a central bore 48 which extends from top to bottom therethrough and through said boss. A cap 49 (FIG. 2C) threadedly engages the boss 47 to support a tube 50 the lower end of which engages in the bore 48. The cap 49 has a depending internally threaded hollow neck 51 which is normally closed and sealed by threaded plug 52. The upper end of the tube 50 seats in a downwardly opening centrally disposed socket 53 of the plug 36. An elongated sealed container 54, preferably of plastic or rubber, is disposed in and extends from end-to-end of the tube 50 and is filled with an expansible gas, such as carbon dioxide or with compressed air.

The plug 36 has an upwardly extending internally threaded annular flange 55 in which the externally threaded lower end 56 of a housing member 57 threadedly engages. The housing member 57 is of circular cross section, as seen in FIGURE 8, and has a head 58 defining its upper end. As best seen in FIGURE 3, the housing member 57 combines with the plug 36 to form a chamber 59. The head 58 has a downwardly opening frusto-conical cavity 60 forming a downwardly opening valve seat, the upper end of which communicates with a restricted central bore 61 of the head 58 which opens upwardly thereof into an annular externally threaded flange 62, constituting the upper end of the head 58. The plug 36 has a ring of spaced openings 63 forming ports connecting the chamber 59 to the annular chamber 64 formed by the tube 32 and the plugs 33 and 36.

A tubular guide member 65 is disposed axially in the chamber 59 and has its lower end threadedly engaging in a centrally disposed threaded opening 66 of the plug 36 which opens downwardly therethrough into the socket 53, so that the lower end of the guide 65 abuts the upper end of the container 54. The guide 65 has a restricted bore portion 67 to slidably receive and guide a valve stem 68 which extends downwardly from a valve 69. The guide 65, between the bore portion 67 and the plug 36, has ports 70 opening outwardly of the lower portion of the bore thereof into the chamber 59. The part of the bore of the guide 65, disposed above the restricted bore portion 67, defines an upwardly opening socket 71 in which the lower end of a compression spring 72 seats. The spring 72 surrounds the upper portion of the valve stem 68 and has its upper end bearing against the under side of the valve 69.

The valve 69 is cone shaped and is normally held by the spring 72 seated in the valve seat 60 for closing the upper end of the chamber 59. As seen in FIGURE 2B, as thus disposed, the upper end of the valve 69 extends through the opening 61. The valve 69 has an annular groove 73 intermediate of its ends containing an O-ring 74 of rubber or other suitable material, providing an effective seal between the valve 69 and the valve seat 60 when the valve is in its closed position of FIGURE 2B. The diameter of the valve 69 at its lower large end is substantially equal to the diameter of the chamber 59 below the valve seat 60, so as to have a relatively close fitting engagement 75

therewith. The bottom portion of the periphery of the valve 69 has notches 75 forming passages between the lower portion of chamber 59 and the valve seat 60, when the valve is in an open position. The valve stem 68 has a pointed lower end 76 which is disposed in the guide 65, above and spaced from the container 54, when the valve 69 is in a closed position, as seen in FIGURE 2C.

An upper housing member 77, of circular cross section, has a lower end which is internally enlarged and internally threaded, as seen at 78, which is connected to the flange 62, and a tapered upper end 79 forming a frusto-conical flange which terminates a threaded opening 80. A tube 81 has a lower end threadedly engaging in the opening 80 for supporting said tube above the housing 77. The housing 77 defines an upper chamber 82.

The plug 36 has an internally enlarged and internally threaded annular top flange 82 which surrounds the lower portion of the annular flange 55 to receive an externally restricted and externally threaded lower end 83 of a large tube 84, which is thereby threadedly connected to the collar 31. The tube 84 extends upwardly to beyond the upper end of the tube 81, as seen in FIGURE 2B, and is disposed around and spaced from the housings 57 and 77. A plug 85 is secured in an upper end of the tube 84 and has a central opening 86 in which the upper end of the tube 81 is secured. The top of the plug 85 and the upper end of the tube 81 are dished as seen at 87 to provide a guide for the lowering and anchoring unit 22, as will hereinafter be described. The tube 84 combines with the plugs 36 and 85 to form a relief chamber 88. A check valve 89 has a pipe extension 90 which threadedly engages at its lower end in a threaded opening 91 of the flange 79, for supporting the check valve on the upper housing member 77 within the relief chamber 88, and in communication with the chamber 82. The check valve 89 will hereinafter be described.

The lowering and anchoring unit 22 includes a tubular sheath 92 composed of threadedly connected tubular sheath sections 93, 94, 95, 96, 97, and a head section 98 which is threadedly connected to the upper end of the upper tubular sheath section 93, as seen in FIGURE 2A. An electric wire 99 extends downwardly through a bore 100 of the head section 98, through the upper sheath section 93 and into the sheath section 94 disposed directly therebeneath. Wire 99 is connected to an explosive containing cartridge 101 which is contained in the sheath section 94. The conductor wire 99 is of a conventional type covered with electrical insulation. Wire 99 extends upwardly from the head 98 through a tubular metal casting 102 which is secured at its lower end to the head 98 for supporting the unit 22 and the plug 21.

A piston 103 is slidably disposed in the sheath section 95, beneath and spaced from the explosive charge 101, and has a piston rod 104 extending downwardly therefrom and which is connected to the upper end of an upper plunger section 105 at its lower end. The plunger section 105 is contained in the lower portion of the sheath section 96 which has a restricted bore portion 106 disposed above and spaced from said plunger section and forming a guide for the piston rod 104. The lower end of the plunger section 105 has a threaded socket 107 to receive a threaded projection 108, constituting the upper end of a lower plunger section 109 which is contained in the bottom-most sheath section 97. A shear pin 110 extends through the plunger section 105 and the sheath section 96 for holding the plunger 105, 109 positioned as seen in FIGURES 2B and 4.

The lowermost sheath section 97 has oppositely disposed slots 111 which open outwardly of the lower end thereof, each of which accommodates a latch member 112. The latch members 112 are pivotally mounted in the slots 111 on pivot pins 113 and each has a depending latch arm 114 which terminates in an out-turned hook-shaped terminal or finger 115. The latches 112 each have an upwardly extending longitudinally curved cam arm

116, constituting the part thereof disposed above the pivot 113.

A latch retainer 117 is pivotally mounted in each slot 111 on a pivot pin 118, above the latch 112, and includes a depending cam arm 119, the terminal of which bears against the outer concave edge of the cam arm 116 of the latch disposed therebeneath. Each latch retainer has a leaf spring 120 rising from its pivot 118 and terminating in an out-turned hook 121 which bears yieldably against the top wall 122 of the slot 111 thereof.

As best seen in FIGURE 7, torsion springs 123 are wound on the pivot pins 113 and have their outer ends anchored in the sheath section 97 and their inner ends anchored in the latches 112. The springs 123 are wound in directions to urge the latch arms 112 to swing outwardly toward their full line positions of FIGURE 4. Torsion springs 124 are disposed on the pivot pins 118 with their inner ends anchored in the latch retainers 117 and their outer ends anchored in the sheath section 97. The springs 124 are wound in directions for urging the cam arms 119 to swing inwardly toward their full line positions of FIGURE 4.

The plunger section 109 has opposed grooves 125 which are provided with concave bed portions for accommodating the cam arms 116. To apply the retrievable plug 21 and before it is inserted in the upper end of the well casing 126, the lowering and anchoring unit, assembled as heretofore described and as illustrated in FIGURES 2A and 2B, is initially inserted through the tube 81. The latch fingers 115 will initially engage the dished cam surface 87 and will be cammed inwardly thereby from their full line toward their dotted line positions of FIGURE 4, so that the sheath section 97 can enter the tube 81 and move downwardly therethrough to its position of FIGURES 2B and 4. As the latch fingers 115 clear the lower end of the tube 81, the latches 112 will be urged to swing from their dotted line to their full line positions of FIGURE 4 by the springs 123, to cause the fingers 115 to engage the inner surface of the flange 79 for latching the unit 22 to the plug 21. As seen in FIGURE 4, the convex outer sides of the cam arms 116 conformably engaged in portions of the beds of the grooves 125 when the latches 112 are in their full line latching positions. As the latches 112 swing to their full line positions, the latch retainers 117 are oscillated by the springs 124 for causing the cam arms 119 to swing inwardly to their full line positions of FIGURE 4 against the cam arms 116, and for causing the leaf springs 120 to swing outwardly toward the wall of the tube 81. This outward movement of the springs 120 causes the springs to be compressed endwise so that the hook portions 121 thereof are brought into tighter frictional engagement with the slot ends 122 to effectively resist any tendency of the latches 112 to swing back toward their dotted line positions, which would necessitate forcing the retainers 117 to be swung back toward their dotted line positions in FIGURE 4. As seen in FIGURE 2B, sheath section 95 has O-rings 95' to seal the tube 81 when the unit 22 is latched to plug 21.

The plug 21 as thus attached to the unit 22 is lowered into the casing 126 to a desired location. A switch, not shown, located at the surface of the well, is then closed to complete a circuit through the wire 99 to the explosive charge 101 which is grounded through the sheath 92 and metal parts of the plug 21 to the casing 126 to effect detonation of the charge. When this occurs, the explosive charge is channeled and shaped in its passage initially through the bore portion 127 and thence through the flared bore portion 128 (FIGURE 2B) to concentrate the force of the charge against the upper end of the piston 103. The initial impact of the charge against the piston will drive the piston downwardly with sufficient force to sever the shear pin 110. The plunger 105, 109 will be driven downwardly by the force of the explosion from its position in FIGURES 2B and 4 to its position of FIGURE 3. During the initial downward movement of the

lower plunger section 109, the grooves 125 will cam the arms 116 outwardly as the upper ends of said grooves move into contact with said arms, for swinging the latches 112 and the latch retainers 117 back to their dotted line positions of FIGURE 4 and to their positions of FIGURE 3. The plunger section 109 continues to move downwardly through the chamber 82 until the cavity 129 in the head thereof engages the upper end of the valve 69. The valve 69 is then driven downwardly by the plunger section 109 as the lower end thereof moves through the opening 61 and to substantially the position of FIGURE 3. This drives the valve stem 68 downwardly through the guide 65 to cause the pointed end 76 thereof to pierce the upper end of the container 54. The downward movement of the valve 65 compresses the spring 72 which reacts after the valve 69 has reached its position of FIGURE 3 to return the valve to its raised position of FIGURE 2B for closing the valve seat 60 and for retracting the stem 68 out of engagement with the container 54 and back to its position of FIGURE 2C. The compressed air or carbon dioxide gas then escapes through the pierced upper end of the container 54 into the chamber 59, through the ports 70 and back into the chamber 64 through the ports 63, for expanding the tubes 32 and 30. Expansion of the upper portion of the tube 32 stretches and enlarges the sealing rings 39 for bringing said rings into tight sealing engagement with the wall of the casing 126 for sealing off the casing bore 130 above and below the sealing rings 39. Expansion of the lower part of the tube 32 distends parts of the tube 30 which are in registration with the slots 27 and attached to the clamps 28, for forcing the clamps outwardly through the slots 27 to cause the teeth 29 thereof to bite into the casing 126 for effectively retaining the plug against movement lengthwise of the casing. It will be apparent that the upwardly inclined teeth 29 at the lower end of the clamps will effectively resist upward movement of the plug 21, while the downwardly inclined teeth 29 at the upper ends of the clamps 28 will effectively prevent downward displacement of the plug.

Since the plunger section 109 will only be retracted sufficiently by the spring 72 to permit the valve 69 to resume its closed position to prevent escape of any of the compressed medium from the container 54 through the valve seat 60, said plunger section 109 will not return to its position of FIGURE 4 so that the latches 112 and latch retainers 117 will be retained in their positions of FIGURE 3. Accordingly, when an upward pull is exerted on the cable 102, unit 22 will be extracted from the tube 81 and can be recovered.

The nipple 108 is then unscrewed from the socket 107 to detach the bottom plunger section 109; and the bottom sheath section 97 is unscrewed from the sheath section 96. The upper plunger section 105 is then returned to its position of FIGURE 2B and a new shear pin 110 is applied for securing the plunger section 105 to the sheath section 96.

An elongated hammer 131 is then applied to replace the plunger section 109 and the sheath section 97 to convert the lowering and anchoring unit 22 unto the retrieving unit 132 which otherwise corresponds to said lowering unit 22. The hammer 131 has an outer diameter corresponding with the outer diameter of the sheath section 97 and has an internally threaded socket 133 at its upper end in which the threaded nipple 134 at the lower end of the sheath section 96 threadedly engages. A small threaded stem 135 extends upwardly from the bed of the socket 133 and threadedly engages in the threaded socket 107 for threadedly connecting the hammer 131 to the sheath section 96 and the plunger section 105.

The hammer 131 has oppositely disposed outwardly opening grooves 136 and 137 containing latching fingers 138 and 139, respectively, which are pivotally mounted in the lower ends of said grooves by pivot pins 140 and 141, respectively. The hammer 131 has transversely disposed

sockets 142 and 143 which open into the grooves 136 and 137, respectively, and which contain compression springs 144 and 145, respectively. The hammer 131 has a tapered frusto-conical lower end 14 which has a cavity 147 in the end thereof; and an O-ring 148 is disposed in a groove 149 of the hammer which is disposed above and adjacent its end portion 146.

As seen in FIGURE 2B, a housing 150 is secured to the exterior of the tube 81 and is disposed within the chamber 88. The housing 150 has an internally restricted lower portion 151 containing a sliding gate valve 152 having a port 153 which registers with aligned ports 154 and 155 of the tube 81 and housing 150, respectively, in the open position of said valve 152, as seen in FIGURE 2B. A valve stem 156 extends upwardly from the valve 152 through guides 157 and 158 which are attached to the exterior of the tube 81 and disposed in the housing 150. A lever 159 is slidably and pivotally mounted on a pin 160 which spans a slot 161 of the tube 81. The pin 160 engages a slot 162 of said lever. The upper end of the rod 156 is pivoted at 163 to the lever 159. A pull spring 164 is attached at its upper end to the rod 156 and at its lower end to the guide 158 for urging said rod downwardly to move the valve 152 downwardly to a closed position. An O-ring 165 forms a seal around the inner end of the port 155.

When the lowering and anchoring unit 22 is applied to the plug 21, as previously described, it will move the valve 152 to its open position; however, the valve 152 functions only with the retrieving unit 132 and will be returned by the spring 164 to a closed position, as seen in dotted lines of FIGURE 2B, when the lowering and anchoring unit 22 is recovered from the plug 21.

To retrieve the plug 21, the retrieving unit 132 is lowered into the casing 126 and its leading end 146 will engage the surface 87 and be guided thereby into the tube 81. The O-ring 148 upon entering the tube 81 will seal the upper end of said tube and the inner end of the lever 159 will be engaged by the tapered portion 146 and will be swung counterclockwise and also caused to slide on the pin 160 from its dotted line to its full line position of FIGURE 2B, to thereby raise the valve 152 to its open position so that hydrostatic fluids and circulating fluids which have filled said tube and the chamber 82 will escape through the aligned ports 153, 154 and 155 into the relief chamber 88.

As the hammer 131 moves downwardly into the tube 81 the latch fingers 138 and 139 will be swung inwardly into the grooves 136 and 137, respectively, to allow the latch fingers to move downward with the hammer 131 through the tube 81. A sufficient amount of the fluid contained in said tube 81 and the chamber 82 will escape to substantially reduce the pressure in the chamber 82 before the ring 148 passes the port 154 to shut off further escape of the fluid outwardly therethrough. The fluid then remaining in the chamber 82 will be at a sufficiently low pressure to enable it to escape through the valve 89, as it will hereinafter be described in detail.

The hammer 131 will pass downwardly through the chamber 82 and the cavity 147 thereof will strike the top of the valve 69 with sufficient force to force the valve downwardly to its open position of FIGURE 11. In this position of the hammer 131, the latch fingers 138 and 139 will have cleared the lower end of the tube 81 so that the spring 144 and 145 thereof, respectively, may swing said latch fingers outwardly to their latched positions, as illustrated. As thus disposed, the valve 69 will be held open by the hammer 131 and the tapered portion 146 thereof will close the passage 61. However, the head 58 has radial passages 166 opening outwardly into the relief chamber 88 and communicating with the valve seat 60, so that the compressed gas or air in the chambers 59 and 64 can escape past the notches 75 and between the valve 69 and seat 60 to the passages 166 from which the gas can escape to the relief chamber 88. As the pres-

sure diminishes in the chamber 64, clamps 28 will be drawn inwardly and back to their positions of FIGURE 2C by the elastic tube 30, and the sealing rings 39 will contract out of engagement with the wall of the casing 5 126 to thus release the plug 21 from the casing so that it can be retrieved by the tubular casing 102 with the retrieving unit 132.

The check valve 89, as best seen in FIGURES 12 to 17, is of circular cross section and includes an intermediate 10 section 167, end sections 168 and 169, a section 170 as interposed between the sections 167 and 168, and a section 172 which is interposed between the sections 167 and 169. The section 167 has restricted threaded ends 172 and 173 which threadedly engage in internally threaded inner end flanges 174 and 175 of the sections 170 and 171, respectively. The sections 170 and 171 have chambers 174 and 175, respectively, which extend from their remote ends to the portions 172 and 173, respectively, and which chambers are connected with one another by 15 a plurality of passages 176 which extend lengthwise through intermediate section 167.

The bottom section 169 has a threaded nipple 177 which threadedly engages in the upper end of the pipe 90 and which has a bore 178 which extends to the outer end 25 of said nipple which is flared at the inner end of the section 169 to provide a valve seat 179 for a ball valve 180. The inner end of the section 169, which abuts the outer end of the section 171, is recessed, as seen at 181, to accommodate the peripheral portion of a diaphragm 182 which 30 is preferably formed of rubber and which spans the valve seat 179 and has its center bearing against and normally retaining valve 180 in a closed position. Screws 182 which extend lengthwise through the end section 169 around the nipple 177 threadedly engage in sockets 183 of the 35 section 171 for clamping the peripheral portion of the diaphragm 182 between the sections 169 and 171 and for securing said sections together.

The intermediate section 167 has an axial bore 184 opening in to the chamber 175 and which contains a 40 plunger-like spring abutment 185 having an O-ring 186 disposed in an annular groove 187 thereof for sealing the bore 184. A compression spring 188 has one end seating in a socket 189 which opens outwardly of the outer end of said abutment 185 and an opposite end seating in a 45 cup 190 which is disposed in the chamber 175 and which rests centrally on the diaphragm 182. The diaphragm 182 has a series of small apertures 191 between the cup 190 and the part there which is clamped in the recess 181, as seen in FIGURES 13 and 17.

The restricted inner end of the bore 184 intersects with the inner end of a radial bore 192 of the section 176 which is threaded to receive an adjusting screw 193 having a conical inner end 194 which engages a frusto-conical inner end 195 of the abutment 185. Accordingly, when the screw 193 is advanced inwardly, the surface 194 by camming engagement with the surface 195 will displace the abutment 185 outwardly or downwardly of the bore 184 for increasing the pressure of the spring 188.

As seen in FIGURE 12, the exterior of the section 167 has a dished ring portion 196 surrounding the bore 192 and containing circumferentially spaced substantially hemispherical indentations 197 which are preferably designed by indicia 198 representing pressure in pounds. A spring arm 199 extends transversely from the adjustment screw 193 and has an inturned rounded terminal 200, seen in 65 FIGURE 13, disposed to yieldably seat in any one of the indentations 197. Thus, it will be seen that the spring element 199 will latch the screw 193 against rotation in different adjusted positions, and when forcibly turned its end 200 will ride into and out of engagement with the 70 depressions 197.

An axial bore 201 opens through the outer end of the other end section 168 and has an inner end communicating with an inner hemispherical-shaped recess 202 which opens 75 through the inner side of the section 168. The section 168

at its inner side has an annular recess 203 to accommodate the peripheral portion of an elastic rubber diaphragm 204 which is secured therein by the screws 205 which extend inwardly through the section 168, through the peripheral portion of the diaphragm 204, and which are anchored in threaded sockets 206 of the section 170.

The other end of the section 167 has a bore 184' opening into the chamber 174 and containing abutment 185'. A threaded radial bore 192' contains an adjustment screw 193' which contacts the plunger 185'. The parts 184' and 185' correspond with the parts 184 and 185, respectively, and the parts 192' and 193' correspond with the parts 192 and 193, respectively, except that the parts 192' and 193' are oppositely threaded from the parts 192 and 193. The screw 193' is locked in different adjusted positions by a spring 199' in the same manner as the screw 193.

One end of a spring 207 seats in the abutment 185' and extends therefrom into the chamber 174 and has its opposite end bearing against a ball 208 which is also disposed in said chamber between the spring 207 and the center of the diaphragm 204. The diaphragm 204 has a ring of apertures 209 spaced from the center thereof, as seen in FIGURES 13 and 14. As seen in FIGURE 13, the spring 207 is heavier and stronger than the spring 188, and the diaphragm 204 is thicker and less elastic than the diaphragm 182.

The combined capacity of the apertures 191 and the combined capacity of the bores 176 is each greater than the combined capacity of the apertures 209. Assuming now that the lowering unit 22 is being extracted from the plug 21, as previously described, and until said unit clears the plug substantially no pressure will exist in the chamber 82, and the parts of the valve 89 will be disposed as seen in FIGURE 13. As the lowering unit clears the plug, hydrostatic and circulating fluids will fill the chamber 82 through the tube 81 to create a high pressure therein. A part of this fluid will pass outwardly through the pipe 99 and bore 178 to unseat the valve 180 so that the fluid can flow through the apertures 191. The pressure of the fluid against the under side of the diaphragm 182 will distend said diaphragm into the chamber 175 and compress the spring 188.

The fluid will flow from the chamber 75 through the passages 176 to fill the chamber 174 and some of this fluid will escape through the apertures 209 and the bore 201 from the check valve. However, due to the lesser capacity of the apertures 209, the pressure will build up in the chamber 174 which will act with the spring 207 for forcing the diaphragm 204 outwardly until it reaches a fully distended position, as seen in dotted lines of FIGURE 13, against the surface of the cavity 202. The ball 208 will then be lining or filling the substantially hemispherical central portion of the diaphragm 204 so that the apertures 209 will be sealed by their engagement against said cavity surface and to some extent by being engaged by the ball 208, to thus shut off the flow from the check valve 89. It will thus be seen that the check valve will close in response to a high pressure in the chamber 82.

Thereafter, when the retrieving unit is applied and the pressure in the chamber 82 is partially dissipated by opening of the valve 152, as previously described, this diminishing of pressure in the chamber 82 will cause a reduction of pressure in the chambers 175 and 174 so that the diaphragm 204 can move out of contact with the hemispherical surface of the cavity 202 to expose the apertures 209 to allow escape of the fluid from the chamber 174. As the pressure of said chamber diminishes the diaphragm 204 will gradually return to its full line position of FIGURE 13. Reduced pressure in the chamber 82 will also permit the spring 188 and diaphragm 182 to close or partially close the ball valve 180, when the pressure in the chamber 175 is not much greater than the pressure in the chamber 82. However, as the pressure diminishes in the chamber 174 it will equalize with the chamber 175, and when this pressure has become sufficiently more

than the pressure in the chamber 82, the valve 180 will again open to allow further escape of the fluid from the chamber 82. However, this fluid will be at a relatively low pressure incapable of returning the diaphragm 204 to its dotted line position of FIGURE 13, so that the valve 89 will remain open to permit escape of the fluid at a low pressure. The tube 84 contains a drainage port 210 normally sealed by a threaded plug 211 which can be removed for draining the chamber 88 after the plug 21 has been retrieved.

Various modifications and changes are contemplated and may obviously be resorted to without departing from the function or scope of the invention, as hereinafter defined by the appended claims.

I claim as my invention:

1. A device for sealing a well casing bore comprising a bridging plug including an elongated plug body, said body having an expandible lower portion, a normally sealed chamber formed partially by said lower portion, elastic sealing rings surrounding a part of said expandible lower portion, a sealed container containing an expandible gas, a piercing member slidably mounted above said container; a lowering unit having a lower part fitting slidably and detachably into an upper part of said plug body and by which the plug body is adapted to be lowered into a well casing, latch means forming a part of said lowering unit by which said lower part is releasably latched in the plug body, a plunger slidably disposed in the lower part of said lowering unit, means forcibly driving said plunger downwardly from the lower part of said lowering unit through a part of said plug for engaging and driving the piercing member downwardly for rupturing said container to release the gas therefrom to pressurize and expand said lower portion for expanding said sealing rings into sealing engagement with the well casing, and said plunger including a part engaging said latch means to effect unlatching thereof when the plunger is driven downwardly to permit said lowering unit to be retrieved from the plug after the plunger has actuated the piercing member a first housing connected to and extending upwardly from a part of the expandible lower portion and defining an upper part of said expandible chamber, a second housing connected to and extending upwardly from the first housing and defining an upper chamber, a passage connecting said chambers and including a valve seat, an inner tube extending upwardly from said upper housing and communicating with the upper end of said upper chamber, an outer tube connected to a part of said expandible chamber and extending upwardly therefrom and surrounding said housings and the inner tube, a plug sealing the upper end of the outer tube to the inner tube and combining with said tubes to define a relief chamber, a valve connected to an upper end of said piercing member and disposed in said first housing, a spring urging said valve upwardly into seating engagement with said valve seat for closing the passage between the upper chamber and said normally sealed chamber and for normally retaining said piercing member in a retracted position out of engagement with said container; a retrieving unit adapted to be lowered into the well casing including a hammer defining a lower leading end thereof receivable into the plug through said inner tube for passage downwardly through said inner tube and said upper chamber to engage and unseat said valve and for sealing the upper end of the passage connecting the upper chamber and said sealed chamber, said lower housing having ports extending outwardly from the valve seat and opening into the relief chamber for escape of the gas from the sealed chamber to permit the expandible lower portion and said sealing rings to retract, and spring urged latch members carried by said hammer for latching the hammer to the upper housing with the hammer disposed to seal the upper end of said passage to permit the plug to be retrieved from the well casing with said retrieving unit.
2. A device as in claim 1, normally closed valve

means forming a part of said plug and actuated by said retrieving unit entering said inner tube for opening a passage between the lower portion of the inner tube and the relief chamber to permit escape of hydrostatic and circulating fluids from said inner tube and upper chamber into said relief chamber after the upper end of the inner tube is sealed by the retrieving unit.

3. A device as in claim 2, a check valve forming a part of said plug discharging into said relief chamber and communicating with said upper chamber, said check valve opening in response to a low pressure and closing in response to a high pressure whereby said check valve will open after the retrieving unit has entered said inner tube and has moved downwardly therethrough to seal said relief valve for dissipating the fluid remaining in said upper chamber into said relief chamber.

4. A device for sealing a well casing bore comprising an elongated plug having a normally sealed chamber defining a lower part thereof and a relief chamber defining an upper part of the plug, said plug having an expandable portion constituting a lower part of said sealed chamber, elastic sealing rings engaging around and supported by said expandable portion, a sealed container disposed in said sealed chamber and containing an expandable gas, an upper chamber connected to and rising from said sealed chamber, a tube connected to and extending upwardly from said upper chamber and opening through an upper end of the plug; a lowering unit including a lower part insertable through said tube into said upper chamber, latch means carried by said lower part for releasably latching the lowering unit to the plug whereby the plug is adapted to be lowered into the well casing by the

lowering unit, explosive means carried by said lowering unit and operable to produce puncturing of said sealed container to release the gas therefrom to pressurize said sealed chamber for expanding the expandable lower portion to cause the sealing rings to assume sealing engagement with the well casing and to effect release of said latch means to permit the lowering unit to be retrieved from the plug.

5. A device as in claim 4, a passage connecting said sealed chamber and relief chamber, and a valve normally closing said passage; a retrieving unit adapted to be lowered into the well casing including a lower portion receivable through said tube and upper chamber for unseating the valve for depressurizing the sealed chamber to release the plug from the well casing, and latch means carried by said lower part of the retrieving unit for latching the retrieving unit to the plug for retaining said valve in an open position and to permit the plug to be retrieved from the well casing with the retrieving unit.
